PAUL A. SCHUCHART, OF PORTLAND, OREGON.

DRINKING-SPOUT ATTACHMENT FOR FAUCETS.

1,067,443.

Specification of Letters Patent.

Patented July 15, 1913.

Application filed February 28, 1913. Serial No. 751,370.

To all whom it may concern:

Be it known that I, PAUL A. SCHUCILART, a subject of the Empire of Austria-Hungary, and a resident of the city of Portland, county 5 of Multnomah, State of Oregon, have invented a new and useful Improvement in Drinking-Spout Attachments for Faucets, of which the following is a specification.

My invention relates to devices intended 10 for being attached to water faucets for the purpose of directing the stream of water to flow as a vertical jet, so that a person may conveniently drink from the same without using a cup.

15 The object of my invention is to provide a simple, inexpensive, sanitary device which may be easily attached to or detached from any water faucet without requiring the use of supplementary plumbing fixtures, or de- 20 facing those already installed; and, furthermore, a device which will not in any way interfere with the normal operation and use of the water faucet for other purposes.

Another object of the invention is the pro- 25 vision of a drinking spout attachment of open form whereby absolute cleanliness may be obtained at all times, thus satisfying all sanitary requirements as the open or ex- 30 posed surface of the spout, as distinguished from those spouts heretofore known which have been of tubular form, permits cleaning or wiping at any time by the user or by an attendant without requiring detachment or the use of special appliances.

35 The invention consists, first, of a drinking spout of open or channel form; second, a spout of that character which is adapted to be moved laterally into and out of operative position when applied to a faucet; third, a 40 spout of the character set forth having a vertically adjustable connection for fastening it to a faucet, whereby the spout may be adjusted vertically to adjust the jet of water issuing therefrom.

45 In the accompanying drawings: Figure 1 is a side elevation of a water faucet showing my device attached thereto; my device is shown in longitudinal vertical section so as to illustrate more clearly its construction; 50 this view also illustrates how the stream of water is directed from the faucet so as to make it convenient for a person to drink from such stream. This view further shows how the spout member of my device may be 55 adjusted in order to properly position the stream of water; Fig. 2 is a plan detail of

the drinking spout of my device without the attaching means; this figure illustrates the adjustments of which the spout member is capable; the broken outlines of the spout 60 showing the latter so moved as to permit the normal use of the faucet; Fig. 3 shows, on a larger scale, a cross section of the faucet, and the means whereby the drinking member of my attachment is clamped to any 65 water-faucet; this view is taken approximately on the line 3-3 of Fig. 1; and Figs. 4 to 6 are cross-sectional views taken approximately on lines 4-4, 5-5, and 6-6 of Fig. 1 respectively.

70 My attachment consists of a spring-band, b, adapted to fit over the spout of any common faucet. To the band b is secured a U-shaped bracket, c, by means of a bolt and nut e, as shown in Figs. 1 and 3. A spring- 75 steel retaining finger d is fastened to one leg of the bracket c, as convenient, for example the bolt e and a rivet f. The rear end j of the spout g is formed as an ear, by means of which the spout is rotatably bolted to the 80 lower portion or cross-bar of the bracket c. The ear j is so made that when rotated on its pivot (the bolt) k, as shown in the broken lines of Figs. 2 and 3, it will bear against and push outward the spring mem- 85 ber d. And after it has been rotated to lateral position, the spring member d will act to hold said spout in place. The spring d will serve in like manner for holding the 90 spout g in drinking position.

95 The drinking spout g is curved to the form shown in Figs. 1, 4, 5 and 6, so as to turn the stream of water emitted from the faucet from its downward to an upward direction, as illustrated in Fig. 1. The drink- 100 ing spout g is made in the form of a sluice or channel. The discharge end of the spout g is tapered as shown, in order to render it more convenient when applying the mouth for drinking. The sides h are made higher 105 at the two extremities (see Figs. 4 and 6) than at the middle, in order that an ample volume of the stream of water flowing from the faucet, a, will be retained by the spout; and, furthermore, making the sides higher 110 at the forward tapered end of the spout causes the stream of water to be so guided as to bring it to a proper form for use at the discharge or drinking end of the spout. By having the sides lower at the middle por- 115 tion of the spout, the surplus water may overflow.

When water has been turned off, after having used my drinking spout, a small amount would normally remain in the lowest or middle portion of the spout. To drain such water, I have drilled a small drain-orifice at *i*.

Being of open or channel form, my spout can be wiped out by the user or an attendant at any time without requiring detachment 10 from the faucet or the use of special appliances which is a decided advantage over those spouts which are of tubular construction and require detachment or a special appliance to clean them and whose interior 15 cannot be observed by the user, whereas all parts of my spout are exposed and readily observable.

I claim:

1. A drinking spout of open channel form 20 arranged to direct a downwardly flowing stream of liquid under pressure upwardly in

the form of a drinking jet, and means for fastening said spout to a faucet.

2. A drinking spout of open channel form arranged to direct a downwardly flowing 25 stream of liquid under pressure upwardly in the form of a drinking jet, and means for fastening said spout to a faucet, said spout being movable laterally into and out of operative position in relation to the 30 faucet.

3. A drinking spout of open channel form arranged to direct a downwardly flowing stream of liquid under pressure upwardly in the form of a drinking jet, and means for 35 fastening said spout to a faucet, said spout being adjustable vertically to adjust the jet of liquid issuing therefrom.

PAUL A. SCHUCHART.
